UNITED STATES PATENT OFFICE.

HERBERT L. G. MOORE, OF RICHMOND HILL, NEW YORK, ASSIGNOR OF ONE-HALF TO HIMSELF, AND ONE-HALF TO HENRY A. VREELAND, OF NORTH PATERSON, NEW JERSEY.

GREASE-PROOF PAPER VESSEL.

1,041,504.

Specification of Letters Patent.

Patented Oct. 15, 1912.

Application filed May 23, 1912. Serial No. 699,097.

To all whom it may concern:

Be it known that I, HERBERT L. G. MOORE, a citizen of the United States, residing at Richmond Hill, in the county of Queens, State of New York, have invented an Improvement in Grease-Proof Paper Vessels, of which the following is a specification.

My invention relates to a sealed paper vessel designed for holding oils and greasy substances, and its object, is to render the same proof against leakage of the most penetrating of such substances, and with this object in view I provide a cylindrical body provided with a bottom and cover each part being formed of a piece of paper of the desired thickness, cut out of the proper shape and each covered on both sides with a sheet of grease proof paper caused to adhere to the straw or other paper by shellac or other suitable adhesive material.

I am aware that paper vessels have heretofore been constructed of a strip of paper wound upon itself with layers of paraffin paper interposing, and also that vessels of paper have been made with a lining of parchment or water-proof paper, and for this reason my invention is limited to the details of construction hereinafter more particularly described, its essential feature being the production of a vessel of this character wherein the cut edge of the interior seam or lapped portion of the body and also the edges of the cover and bottom of the vessel are protected against contact with the contents of the vessel which would otherwise ooze through the straw paper and injure the appearance of the vessel as well as dry out the contents.

In the accompanying drawing, in which like reference characters indicate like parts throughout the several views; Figure 1 is a vertical section illustrative of a vessel constructed according to my invention, but showing the parts each in one thickness to accommodate space on the drawing. Fig. 2 is a sectional plan in enlarged size of a portion of the body part taken at a point indicated by the broken line $\alpha\alpha$ Fig. 1 to illustrate the folds. Fig. 3 is a sectional view also in enlarged size of the upper left hand portion of a vessel constructed according to my invention. Fig. 4 is a similar view of the lower right hand portion.

1 indicates the body portion of a vessel which is preferably cylindrical and which

may be of uniform circumference or tapered from top to bottom. 2 indicates the bottom of the vessel, and 3 the cover of the same. These parts are each formed of a piece of straw paper or other suitable paper a , and covered on each side with grease-proof paper b . These parts 1, 2 and 3, are cut of the desired shape according to the shape of the vessel to be formed thereby. The grease proof paper b , is caused to adhere to the paper parts a , by any suitable adhesive material, preferably shellac. At a predetermined distance from the upper edge of the body portion, an annular groove 4 is formed in the inner surface of the vessel, while the upper edge of the body portion is doubled inwardly all around the vessel so that the edge of this doubled-in portion extends only to the upper edge of the annular groove 4.

The cover 3, has its edge folded upwardly upon itself, which folded-over portion is caused to closely adhere to the top surface of the cover by any suitable adhesive material. The cover 3 is of a shape corresponding with the shape of the upper part of the vessel and is of a size adapted to be forced into the annular groove 4, so that it will fit snugly therein, and so that the folded edge of the cover extends even with or slightly beyond the edge of the doubled-in portion of the upper edge of the body, which comes in close contact all around the vessel with the upper surface of the fold of the cover, as illustrated in Figs. 1 and 3.

The edge of the lap in the body portion interior of the vessel, I preferably fold over upon itself as shown at d , Fig. 2, and secure it by any suitable adhesive material, preferably shellac.

At a suitable distance from the bottom of the body portion an annular groove 5 is formed similar to the groove 4, in the upper portion, and at a predetermined distance below this groove 5, the body portion is folded inwardly and upwardly with its extreme edge bent at right angles to such upwardly folded portion, so that such right angled edge e , is on a line with and parallel to the lower edge of the annular groove 5 all around.

The bottom 2 has its edge folded over downwardly upon itself, which folded over portion is caused to closely adhere to the under surface of the bottom by any suitable adhesive material. The bottom 2 is of a shape

corresponding with the shape of the lower part of the vessel and is of a size adapted to be forced into the annular groove 5, so that it will fit snugly therein, while the 5 folded over edge contacts with the upper surface of the right angled edge e of the body portion, as shown in Figs. 1 and 4. These parts are all pressed tightly together in forming the vessel, so that the bottom 10 is effectually sealed, but as an additional precaution I prefer to dip the lower portion of the vessel in shellac or other suitable sealing substance. After the bottom has been thus positively sealed, the vessel is 15 ready for filling, and having received its contents, the cover 3 is pressed into the annular groove 4 when the top of the cover is sealed in a similar manner to the bottom, and in addition to such sealing, the 20 entire exterior of the vessel may be coated with the substance known as "water-glass" which gives a finished appearance to the same.

It will be readily seen that in a vessel, 25 constructed according to my invention the body of straw paper and all the cut edges of the several parts are positively protected

from contact with the contents of the vessel, and it is absolutely impossible for the most penetrating substances to leak or ooze 30 through the vessel at any point.

The parts *a* may be formed of straw board or papier-mâché.

I claim as my invention:

A vessel for holding oily substances, having a body portion, a cover and a bottom each composed of a body of paper with a covering on both sides of a piece of grease-proof paper, the body portion having its ends overlapped and pasted together, 35 the inner lap having its edge folded over upon itself and against the outer fold, and secured in such position by adhesive material, said cover and bottom being so formed that when joined to the body portion their 40 edges are free from contact with the contents of the vessel and are protected therefrom by said grease-proof paper covering.

Signed by me this 21st day of May 1912.

HERBERT L. G. MOORE.
